CLAIM

We claim the ornamental design for a lamp, as shown and described.

DESCRIPTION

FIG. 1 is a front view showing our new design for a lamp;
FIG. 2 is a right side view showing our new design shown in
FIG. 1;

FIG. 3 is a left side view showing our new design shown in
FIG. 1;

FIG. 4 is a back view showing our new design shown in FIG.
1;

FIG. 5 is a top view showing our new design shown in FIG. 1;
FIG. 6 is a bottom view showing our new design shown in
FIG. 1; and,

FIG. 7 is a perspective view showing our new design shown in
FIG. 1.

The portions shown in broken lines are not part of the claimed
design but show the environment in which the design is asso-
ciated.
